Michael P. Wadzita, Arlington Heights, Ill., assignor to
Uniroyal, Inc., New York, N.Y., a corporation of New
Jersey

Filed Apr. 3, 1967, Ser. No. 6,493

Term of patent 14 years

(Cl. D9—222)

FIG. 1 is a side elevation of a shipping container showing my new design;

FIG. 2 is an end elevation of a shipping container showing my new design;

FIG. 3 is a top plan view of a shipping container showing my new design;

FIG. 4 is a sectional view along the line 4-4 of FIG. 1;

FIG. 5 is a sectional view along the line 5-5 of FIG. 1;

FIG. 6 is a sectional view along the line 6-6 of FIG. 1; and

FIG. 7 is a sectional view along the line 7-7 of FIG. 1.

In my design of a shipping container the appearance of the bottom is similar to the top, the back to the front and the left end to the right end.

I claim:

The ornamental design for a shipping container, as shown and described.
